LINK CHAIN OR SIMILAR ARTICLE

Mary Frances Reese, Memphis, Tenn.

Application November 18, 1953, Serial No. 27,651

Term of patent 3½ years

(Cl. D45—16)

To all whom it may concern:

Be it known that I, Mary Frances Reese, have invented a new, original, and ornamental Design for a Link Chain or Similar Article, of which the following is a specification, reference being had to the accompanying drawing, forming a part hereof.

In the specification:

Figure 1 is a top plan view of a link chain or similar article showing my new design, with the central portion thereof broken away for convenience of illustration; and

I claim:

The ornamental design for a link chain or similar article, as shown and described.
